[57] CLAIM

The ornamental design for a finger ring or the like, as shown and described.

DESCRIPTION

FIG. 1 is a front perspective view of a finger ring or the like showing my new design;

FIG. 2 is a top plan view thereof;

FIG. 3 is a bottom plan view thereof;

FIG. 4 is a side elevational view, the opposite side being substantially mirror image thereof;

FIG. 5 is a left side elevational view thereof;

FIG. 6 is a right side elevational view thereof.
